UNITED STATES PATENT OFFICE.

JOEL S. COOPER, OF SANTA BARBARA, CALIFORNIA.

THRESHING AND CLEANING MACHINE.

1,172,011.

Specification of Letters Patent.

Patented Feb. 15, 1916.

Application filed August 4, 1915. Serial No. 43,583.

To all whom it may concern:

Be it known that I, JOEL S. COOPER, a citizen of the United States, residing at Santa Barbara, in the county of Santa Barbara 5 and State of California, have invented new and useful Improvements in Threshing and Cleaning Machines, of which the following is a specification.

My invention relates to an apparatus 10 which is designed for threshing and cleaning grains, such as wheat, barley, and the like, and also kindred material, such as beans.

It consists in the combination of two or 15 more threshing, separating and cleaning mechanisms, so disposed, with relation to each other and in a common casing, as to operate simultaneously and successively upon the material to be cleaned.

20 It also comprises details of construction which will be more fully explained by reference to the accompanying drawings, in which—

Figure 1 is a longitudinal, vertical section 25 of the apparatus. Fig. 2 is a plan view. Fig. 3 is a horizontal section in plan, taken on line 3—3 of Fig. 1. Fig. 4 is an end view. Figs. 5 and 6 are detail views showing 30 method of vibrating the hinged edge of concave.

It is the object of my invention to combine in a single homogeneous structure a plurality of operating mechanisms, so related that the material to be operated upon may be 35 first partially threshed and separated from the straw or vines, then passing it immediately through another threshing mechanism by which the work is completed, discharging the greater part of the straw, while the 40 threshed material is received upon vibrating open-work conveyer or conveyers, through which the principal part of the grain may fall, while the chaff and lighter material are carried away by a suitably located blast 45 apparatus. The heavier and more valuable portion is then received upon a second screen and a second blast apparatus operates to further clean this material which is delivered upon a suitable cleaning shoe, and 50 thence is carried by a closed traveling draper and discharged upon a second cleaning shoe where a third air forcing apparatus provides for a further cleaning within this shoe. The 55 material discharged from this shoe may still contain certain unthreshed heads and small material which is passed therefrom through

a third threshing mechanism located to receive the discharge from this shoe, and this material is carried by a closed draper and again delivered upon the final cleaning shoe, 60 by a suitable conveyer or conveyers and any unthreshed heads from the final shoe may be carried out and returned to the third threshing cylinder above, to be finally threshed and the grain delivered into the final cleaning 65 shoe from which it is received by a final conveyer or conveyers and delivered to any suitable point.

The entire apparatus is designed to operate in combination, and is contained within 70 a single casing, with suitably connected driving mechanism to operate all the parts in synchronism.

As shown in the drawing, A is the outer casing of the threshing machine which is of 75 a sufficient length and height to contain the necessary apparatus. This machine is designed to remain stationary at some point while in operation, and to it the grain or material to be threshed is brought by header 80 wagons or equivalent conveyers, (not here shown) and delivered upon an endless traveling belt, as at 2; this belt passing around conveying drums or pulleys located in the upper front portion of the casing, as shown. 85 This traveling carrier delivers the straw to a threshing mechanism composed of a revolving toothed cylinder 3 and a concave frame 4 with coacting teeth and a vibrating hinged front vibrated by shoes 29 attached 90 to shaking tables or screens 5 and 7; these devices being of the usual construction of threshing cylinders.

The grain is more or less cleaned and separated from the straw and is then delivered 95 and received upon a combined screen and conveyer 5, which is located below and to the rear of the threshing cylinder and suspended by links 25. Upon this conveyer the principal portion of the straw and larger 100 waste material is received, and whatever portion of it has not been completely threshed, so as to separate out all of the grain, is carried by the conveyer and delivered to a second threshing mechanism, consisting, as before, of a toothed cylinder and coacting concave, as at 6. From this cylinder any more grain separated will fall upon the conveyer 4' below. This screen 4' and shoe 9 is connected to screens 5 and 7 by an 105 extension of links 25, and the straw continues to be carried outwardly by a vibrat-

ing conveyer 7, similar to the one described at 5. From this point the straw, which is now denuded of grain, will be delivered over the tail of the apparatus either to fall upon 5 the ground, or to be received or picked up by any supplemental devices for conveying it away.

In many cases it will be found that the second threshing mechanism 6 will not be 10 required, under which conditions the cylinder and its shaft may be lifted out of the journal boxes and the concave may be also removed; to facilitate this a portion of screen 5 is hinged as shown at 30. The two 15 vibrators 5 and 7 may then be connected by a short, similar section, so that the whole of this vibrating conveyer will be in a line, and the straw will be conveyed out and discharged without the intervention of the second 20 threshing. This second threshing is particularly useful upon grain which may be damp and tough and not easily separated from the straw and husks.

The vibrators are operated by means of 25 cams, and return springs. A cam shaft is journaled across the machine near the conveyer as at 22, and by means of suitable lugs on the conveyer the rotation of the shaft will cause the cams to engage the lugs 23 30 on the conveyer and reciprocate the conveyer. Stiff springs 24 are designed to be attached to the frame upon the conveyer, in such a way that as soon as the cams have released the conveyer, the springs will act 35 to throw the conveyer back with a jerk or snap, which being stopped abruptly, will cause the material upon the conveyer to move toward the rear by a series of continuous short movements by which the straw 40 gradually reaches the second threshing mechanism, or if it is absent, the discharge end of the carrier. The threshed grain heads and heavier chaff will fall through this conveyer, which is in the form of open 45 or separated transverse slats, and the grain thus falling through will be received upon the second conveyer 4'. This conveyer is designed to retain any partially threshed grain and to deliver it into a receiving shoe 16.

In the space beneath the feeder 2 and the threshing cylinder 3 is located a centrifugal blast fan 10 which may be driven by pulleys upon the threshing machine shaft and the fan shaft and a belt between the two. A direction board 11 serves to deflect the current of air from this fan so that it passes beneath and through the screen conveyer 4', also through the slotted shaking table 5, so 60 as to drive out the lighter worthless chaff which is discharged toward the rear end of the machine by this blast.

In order to regulate the blast, I have shown a number of deflectors 12 mounted 65 and turnable upon horizontal shafts, so that

the angle of the deflectors may be changed and the discharge through the conveyer screen regulated. A regulating door 12a controls the amount of air discharged by the fan. In order to prevent the material from being thrown off at one side or the other of the conveyers, I have shown sloping sides converging toward the conveyer, whereby the grain and material is held toward the center and prevented from falling off at the side edges.

The shoe 9 will have received the grain and partially threshed material which is still valuable from the upper carriers 5 and 7 and delivered from the end of the carrier 8 4. This shoe 9 is suspended and agitated in the usual manner for such shoes and provided with screen surfaces, and a second fan or blast apparatus 13 is located so that it discharges air beneath the shoe 9 to drive 85 off any remaining chaff. The material that does not pass through the screens of the shoe 9 will be delivered over the end of the shoe and a small threshing mechanism 14 located just beneath the discharge end of 90 the shoe, will receive unthreshed heads and material falling over the end of this shoe and complete the threshing of these heads. The grain falling through the shoe and also delivered from this last threshing mechanism 95 will be received upon a canvas conveying belt or draper 15 which carries it back to the vicinity of the fan casing 13 and it is dropped thence upon the final shoe 16 containing the usual screen and sieves. A 100 final fan 17 furnishes air, a blast of which is directed through the screens 16 so as to discharge any remaining chaff or worthless material, and the grain which falls upon the lower screens of the shoe will be delivered to 105 a worm conveyer 18' by which it is delivered at the side of the machine and may be delivered either directly into sacks or receivers, or it may be delivered to elevators which will raise it to a desired point of delivery. 110

The material which is discharged at the end of shoe 16 will be received into a trough or conveyer 19 from which an elevator conveys the material to shoe 9 and the threshing cylinder 14 which is located at the 115 mouth of the shoe 9. This material that is thus raised to the final threshing, may consist of broken heads that may have been partially threshed and separated from the straw or grains, the husk of which is so tough that it has not been removed by the previous threshing, and this last threshing is designed to complete the cleaning of the grain to such an extent that no supplemental grain cleaner such as is usually employed with threshing 120 machines will not be needed. The endless conveyer belt 20 extends horizontally within the lower part of the machine and is provided with inclined side guards 21 by which any falling material will be directed upon 125 130

the belt. This belt receives both threshed or unthreshed heads which may fall through the conveyers above, and carries such material backward and delivers it upon the final vibrating shoe 16, journaled upon runners 27 and vibrated by mechanism as shown at 26, where the clean grain passes through the screens and is delivered to the final screen conveyer 18, which is connected to screen 16. Any remaining unthreshed heads or material needing further treatment is delivered to the rear screen conveyer and elevated to the thresher 14, as previously described.

Having thus described my invention, what I claim and desire to secure by Letters Patent is—

1. In an apparatus of the character described, a plurality of threshing cylinders, a feeding device, intermediate shaking tables substantially in a horizontal plane, a screen conveyer located below the tables, adapted to receive material passing through said tables, a fan discharging air through said conveyer, a shoe upon which a portion of the threshed material is received, an endless traveling conveyer upon which material is received directly from the shoe, a shoe upon which said belt conveyer discharges, a receiving conveyer into which the last named shoe delivers, an elevator by which material so received is raised to the proximity of the first named shoe, and a threshing mechanism to which material so raised is delivered for re-threshing.

2. In an apparatus of the character described, threshing cylinders located in a horizontal plane, one at the front, and a second midway of the length of the machine, open slat impulse reciprocating conveyers extending between the threshing members to deliver material from one to the other, a second impulse conveyer extending in line from the second thresher to the rear of the machine, said second cylinder and concave being removable, and a supplemental section of conveyer with means to connect and make the front and rear sections continuous.

3. In a threshing machine, a pair of spaced threshing mechanisms, a table connecting the two mechanisms, said table having a hinged portion adjacent one of said mechanisms to allow the latter to be removed, and a second table extending from said one of the mechanisms and adapted upon removal of the latter to be connected to the first named table.

4. In a threshing machine, an upper threshing mechanism, a table therebeneath, a screen beneath said table at one end of the latter, a shoe beneath the other end of the table and underlying one end of the screen, and a second threshing mechanism beneath the discharge end of the shoe.

5. In a threshing machine, an upper threshing mechanism, a table therebeneath, a screen beneath said table at one end of the latter, a shoe beneath the other end of the table and underlying one end of the screen, a second threshing mechanism beneath the discharge end of the shoe, a conveyer beneath the shoe, a second shoe underlying said conveyer, means to elevate the unthreshed material from the second shoe onto the first shoe and means beneath said table to convey material dropping from the latter to the second shoe.

6. In a threshing machine, a pair of spaced threshing mechanisms, tables underlying the respective mechanisms, a screen underlying one table, a shoe underlying the other table and the discharge end of the screen, a fan for the screen beneath same, and a second fan for the shoe arranged therebeneath.

7. In a threshing machine, an upper threshing mechanism and screen therebeneath, a shoe for receiving the discharge from said screen, a lower threshing mechanism to receive the shoe discharge, a final shoe to receive material from the shoe, and means to convey material from the final shoe to the first shoe.

8. In a threshing machine, an upper threshing mechanism, and screen therebeneath, a shoe for receiving the discharge from said screen, a lower threshing mechanism to receive the shoe discharge, a final shoe to receive material from the shoe, means to convey material from the final shoe to the first shoe, and means to convey material from the screen onto the final shoe.

9. In a threshing machine, an upper threshing means, means to receive material from said threshing means, other threshing means associated with said receiving means, means to convey unthreshed material from said receiving means in a direction opposite to the direction of feed of the material, means beneath the first receiving means to convey unthreshed material therefrom in the direction of feed of the machine, and means to receive said material from both of said conveying means.

10. In a threshing machine, an upper threshing means, means to receive material from said threshing means, other threshing means associated with said receiving means, means to convey unthreshed material from said receiving means in a direction opposite to the direction of feed of the material, means beneath the first receiving means to convey unthreshed material therefrom in the direction of feed of the machine, a shoe common to each of said conveying means and receiving said material from both, and means to elevate the unthreshed material from said shoe to the first receiving means.

11. In a threshing machine, initial threshing means, a screen and a shoe to receive material from said initial means, means associated with said shoe to thresh said material, 5 conveyer means to receive material from said screen, a final shoe to receive material from said conveyer means, and means to elevate the unthreshed material from the final to the first shoe.
- 10 12. In a threshing machine, upper threshing means, lower threshing means, means to convey unthreshed material from the upper to the lower threshing means and means to reconvey unthreshed material escaping from 15 the lower threshing means thereto.
13. In a threshing machine, upper thresh-

ing means, lower threshing means, means to convey material from the upper means in one direction, means to convey material from the lower threshing means in a direction opposite to the direction of movement of the first conveyer means, and means to receive material from each of said conveying means.

In testimony whereof I have hereunto set 25 my hand in the presence of two subscribing witnesses.

JOEL S. COOPER.
